UNITED STATES PATENT OFFICE.

HERBERT R. KEITHLEY, OF BUFFALO, NEW YORK.

CAR-TRUCK.

SPECIFICATION forming part of Letters Patent No. 702,564, dated June 17, 1902.

Application filed January 20, 1902. Serial No. 90,470. (No model.)

To all whom it may concern:

Be it known that I, HERBERT R. KEITHLEY, a citizen of the United States, residing at Buffalo, in the county of Erie and State of New York, have invented new and useful Improvements in Car-Trucks, of which the following is a specification.

This invention relates to a truck for railway-cars in which the side frames are built up of commercial shapes and plates riveted or bolted together.

One of the chief advantages of the well-known "diamond" truck is the truss construction of the side frames, in which practically all of the metal is in the upper and lower arch-bars, which form the compression and tension members of the trussed frame; but these side frames are usually rigidly connected to the journal-boxes and are therefore subjected to severe strains and jars. This type of truck, furthermore, has not the requisite strength for the heavy loads placed upon the same in the use of the modern large steel cars. In the pressed-steel "pedestal-truck," in which springs are interposed between the journal-boxes and the side frames of the truck, the frame is largely relieved of the strains and jars to which the diamond truck-frame is subjected; but these pressed-steel frames are very heavy and are made up of specially-shaped parts requiring expensive and specially-designed machinery for their production.

The object of this invention is to produce a built-up truck-frame constructed of the minimum number of parts, which will have the maximum strength and rigidity for a given weight of metal and which will embody the essential and distinctive features of both the diamond and pedestal types of trucks.

In the accompanying drawings, consisting of three sheets, Figure 1 is a side elevation of a railway-car truck embodying the invention; Fig. 2, an end view of the same, showing one half of the truck-frame in elevation and the other half in section, the plane of the sectional portion being in line 2-2, Fig. 1. Fig. 3 is a perspective view of the truck-frame. Fig. 4 is a side elevation of the truck, showing the use of a bolster therewith. Fig. 5 is an end view thereof, showing one half of the truck-frame in elevation and the other

half in section, the plane of the sectional portion being in line 5-5, Fig. 4.

Like letters of reference refer to like parts in the several figures.

The truck-frame comprises two side frames connected by a transverse transom, each of the side frames being composed of pedestals at or near the ends and connecting-frame members.

A A represent the pedestals, which are preferably, as shown in the drawings, of inverted U shape and formed of angle-bars arranged with one flange a standing vertically and the other flange a' projecting outwardly from the inner edge of the vertical flange. The pedestals straddle the journal-boxes B, as usual, and are guided by the journal-boxes in the up-and-down movements of the truck-frame.

C and D represent, respectively, lower and upper or tension and compression members of the trussed side frames. The tension member is bent to provide horizontal end portions which extend over and rest upon the upper horizontal portions of the outwardly-projecting flanges a' of the pedestals, downwardly-converging inclined portions c', and a central horizontal portion c², connecting the lower ends of the inclined portions. The upper or compression member, as shown in the drawings, is similarly bent to provide the end horizontal portions d, inclined portions d', and a central horizontal connection portion d²; but the inclination of the inclined portions d' of the compression member is much less than that of the tension member, so that the tension and compression members are separated at their middle portions by an intervening space. The tension and compression members are preferably formed of Z-bars arranged with the end portions of their webs standing vertically side by side and outside of and parallel with the vertical flanges of the pedestals A. The lower flanges d³ of the tension and compression members at their ends are superposed and project outwardly above the flange a' of the pedestals, and the upper flanges d⁴ of said members are superposed and project inwardly over the tops of the vertical webs of the pedestals. The tension and compression members are secured to each other at their ends and to the adjacent portions of the vertical flanges of the pedestals

90
95
100

by rivets or the like d^5 . The pedestals and truss members may be reversed, so that the lateral flanges of the pedestals extend inwardly and the upper flanges of the tension and compression members extend outwardly over the tops of the vertical pedestal-flanges without altering the relative arrangement of the several parts.

E represents a horizontal frame member, 10 which connects the lower ends of the two pedestals. This member is preferably in the form of an angle bar or plate with a lower inwardly-projecting flange e , and its ends, which lie flat against the inner faces of the vertical 15 flanges of the pedestals, are secured thereto by rivets or the like e' passing through the pedestal-flanges and the bar or plate. The vertical web of this frame member lies against the inner face of the lower horizontal portion 20 c^2 of the tension member beneath the inwardly-projecting flange thereof.

F represents tie-bolts connecting the legs of the pedestals beneath the journal-boxes. The bolts pass through the lateral flanges of 25 the pedestals and through spacing-sleeves f . A tie of any other desired form may be employed.

The side frames are supported from the journal-boxes, as usual, by springs G, arranged 30 between the tops of the journal-boxes and the horizontal portions of the pedestals. Spring-caps g , of any desired form, are preferably interposed between the tops of the springs and the pedestals. The transom 35 which connects the side frames is shown as composed of two Z plates or bars H, the upper flanges h of which project outwardly or away from each other and the lower flanges h' of which project inwardly or toward each 40 other. Each plate or bar has at its opposite ends vertical flanges h^2 , which are continuations of the top flanges h and extend outward or away from each other and are continued around under the ends of the lower flanges h' 45 of the plates or bars, as indicated at h^3 . These transom plates or bars can be readily made by forming a continuous flange on one longitudinal side and the two ends of a plate and then bending the unflanged side of the 50 plate at right angles to the body of the plate to form the lower flange h' of the transom member. The lower flanges h' of the transom members rest at their ends on the horizontal central portions of the tension members of 55 the side frames, and the end flanges h^2 lie against the outer faces of the webs of the tension members, to which they are secured by rivets or the like h^4 . The upper portions of the ends of the transom members are ar- 60 ranged inside of the webs of the compression members, and vertical plates I are interposed between the webs of the compression members and the end flanges of the transom members. The parts are rigidly connected by riv- 65 ets or the like i , which pass through the plate I and the end flanges of the transom members, through the compression member and

plate, and through the compression-member plate and end flanges of the transom members.

The truck-frame constructed as thus far described and as shown in Figs. 1, 2, and 3 can be used without a truck-bolster, the car being supported directly from the transom. The construction also permits of the employ- 75 ment of a bolster which is supported, as usual, at its ends by springs arranged in the end portions of the transom.

In Figs. 4 and 5 a bolster J is shown, which at its ends rests on springs j , which are supported on plates j' , secured to the bottom flanges h' of the transom members. The bolster may be of any suitable construction. With the truck constructed as thus described two sets of springs are interposed between 85 the journal-boxes and the car-body, one set being arranged between the journal-boxes and the truck-frame and the other set between the truck-frame and the car-body, thereby doubling the spring movement. The 90 truck-frame is thus cushioned between two sets of springs and becomes a much more effective and efficient means for transmitting the load from the moving car to the rails and enables the carrying of a much heavier load 95 without damage to the truck-frame or to the track.

The Z-bar construction gives greater stiffness and transverse strength at the ends of the side frames, which form its pedestal-supports, and great lateral strength and stiffness to resist the side thrusts to which the truck-frame is subjected in rounding curves. The truck-frame is built of very few parts, and the joints between these parts are so arranged 105 that large riveting areas are secured.

I claim as my invention—

1. In a trussed side frame for railway-car trucks the combination of two pedestals, a tension member formed with a vertical web 110 and oppositely-projecting lateral flanges, a compression member formed with a vertical web and oppositely-projecting lateral flanges, the end portions of the webs of said tension and compression members being arranged 115 vertically and secured to said pedestals, and the end portions of the lateral flanges of one of said members being arranged directly above the end portions of the lateral flanges of the other member, substantially as set 120 forth.

2. In a trussed side frame for railway-car trucks, the combination of pedestals each having a vertical web and a laterally-projecting flange, a tension member formed with a vertical web and a horizontal flange, and a compression member formed with a vertical web and a horizontal flange, the end portions of the webs of said tension and compression members being arranged vertically side by side 125 and riveted to each other and to the vertical webs of said pedestals, and the end portions of the horizontal flange of one of said members being arranged directly above the end 130

portions of the horizontal flange of the other member, substantially as set forth.

3. In a trussed side frame for railway-car trucks, the combination of two pedestals each 5 having a vertical and a lateral flange, a tension member formed with a vertical web and oppositely-projecting upper and lower flanges, a compression member formed with a vertical web and a horizontal flange, the end portions 10 of the webs of the tension and compression members being arranged side by side and parallel with the vertical webs of the pedestals, and the end portions of the flanges of said tension and compression members being superposed, and connecting-rivets or the like 15 passing through the vertical webs of said tension and compression members and the vertical webs of said pedestals, substantially as set forth.
- 20 4. In a trussed side frame for railway-car trucks, the combination of two pedestals each having a vertical web and a lateral flange, a tension member formed with a vertical web and oppositely-projecting upper and lower 25 flanges, a compression member formed with a vertical web and a horizontal flange, the end portions 30 of the webs of the tension and compression members being arranged side by side and parallel with the vertical webs of the pedestals, and the end portions of the upper flanges of said tension and compression members being superposed and extending over the vertical webs of the pedestals and connecting-rivets or the like passing through the vertical 35 webs of said tension and compression members and the vertical flanges of said pedestals, substantially as set forth.
5. In a trussed side frame for railway-car trucks, the combination of two pedestals each 40 having a vertical web and a lateral flange, a tension member formed with a vertical web and oppositely-projecting upper and lower flanges, a compression member formed with a vertical web and oppositely-projecting upper 45 and lower flanges, the end portions of the webs of the tension and compression members being arranged side by side and parallel with the vertical webs of the pedestals and the end portions 50 of the upper flanges of said tension and compression members being superposed and extending over the vertical webs of the pedestals and end portions of the lower flanges of said tension and compression members being superposed and being arranged over the 55 lateral flanges of the pedestals, and connecting-rivets or the like passing through the vertical webs of said tension and compression members and the vertical flanges of said pedestals, substantially as set forth.
- 60 6. In a railway-car truck, the combination of two side frames, each composed of two pedestals having vertical webs, a tension member formed with a vertical web and a horizontal flange, a compression member formed 65 with a vertical web and a horizontal flange,

the end portions of the webs of said tension and compression members being arranged side by side and parallel with the vertical webs of the pedestals and the end portions of the horizontal flanges of said members 70 being superposed and extending over the vertical webs of the pedestals, rivets or the like connecting the webs of said tension and compression members to the vertical webs of said pedestals, a transom having vertical end flanges, the lower portions of which are secured to the vertical webs of the tension members, and the upper portions of which are secured to the vertical webs of said compression members, substantially as set 80 forth.

7. In a railway-car truck, the combination of two side frames, each composed of pedestals having vertical webs and laterally-projecting flanges, a tension member formed 85 with a vertical web and a horizontal flange, a compression member formed with a vertical web and a horizontal flange, the end portions 90 of the webs of said tension and compression members being arranged side by side and parallel with the vertical webs of the pedestals, and the end portions of their horizontal flanges being superposed and extending over the vertical webs of said pedestals, rivets or the like connecting the end portions of the 95 webs of the tension and compression members together and to said pedestals, a transom arranged between said side frames and composed of two **Z** members each having vertical end flanges, rivets or the like securing the 100 lower portions of the end flanges of the transom members to said tension members, a plate arranged between the upper portions of the end flanges of said transom members and the vertical webs of the compression members, 105 and rivets or the like connecting said plates to said compression members and to the end flanges of said transom members, substantially as set forth.

8. The combination of two side frames each 110 composed of pedestals, a tension member formed with a vertical web and oppositely-projecting lateral flanges, a compression member formed with a vertical web and oppositely-projecting lateral flanges, the end portions of 115 the webs of said tension and compression members being arranged vertically and secured to the pedestals, and the end portions of their flanges being superposed, a transom connecting said side frames, a bolster, and 120 springs arranged between the end portions of the transom and the bolster, substantially as set forth.

Witness my hand this 9th day of January, 1902.
